UNITED STATES PATENT OFFICE.

CHARLES HASKELL CLARK, OF BERKELEY, CALIFORNIA, ASSIGNOR TO CLARK
PEDMOBILE CORPORATION, OF BROOKLYN, NEW YORK.

SKATE.

1,379,250.

Specification of Letters Patent.

Patented May 24, 1921.

Application filed November 15, 1916. Serial No. 131,581.

To all whom it may concern:

Be it known that I, CHARLES HASKELL CLARK, citizen of the United States, residing at 1626 Spruce St., Berkeley, in the county 5 of Alameda and State of California, have invented certain new and useful Improvements in Skates, of which the following is a specification.

The primary objects of the present invention are to provide an offset wheel or cycle skate so arranged that the foot will lie normally in its natural angular relation to the leg of the wearer of the skate at all times excepting during application of the brakes, 10 or in other words, at right angles to the leg, to allow play or rocking of the foot laterally on the ankle, and to provide means for braking the rear wheel, such means being operated by a downward movement of the 15 toe relative to the heel, such movement most naturally being given by a forward movement of the foot, either alone or in conjunction with a lateral and rocking movement of the foot, in the latter case the movement of the foot forward of the line or 20 center of gravity of the body being much less than in the former and resulting in a more abrupt application of the brake, due to quicker actuation of the braking mechanism 25 and the ability to place more weight on the rear wheel; and to provide for the greatest amount of control in steering when an abrupt turn is necessary and to give the greatest amount of freedom and ease when traveling at high speed or in climbing hills or skating 30 against the wind.

The result of having the brake applied by the forward movement of the foot is that by so doing so long as the brake is on the foot 35 will be slightly in advance of the center of gravity of the wearer's body and in case the brake be applied too abruptly the center of gravity will be carried forward by the momentum of the wearer's body until nearly 40 even with, or even with or slightly in advance of the foot, thus easing up on, or entirely releasing, the brake, thus automatically regulating the action of the brake and saving the wearer from a bad fall.

50 Figure 1 is a side elevation of a left foot skate embodying my invention;

Fig. 2, a top plan view thereof;

Fig. 3, a detail view of the forward part 55 of a slightly modified form in which the front wheel is provided with a steering

knuckle and means for operating the same; and

Fig. 4, a top plan view of the modified form, omitting the rear wheel and brake mechanism.

Referring now in detail to the drawings, 2 indicates the front wheel mounted on the end portion of the forward inwardly presented arm of a crank-shaped frame 6 and 4 indicates the rear wheel mounted on the end portion of the rear and outwardly presented arm of said frame, the intermediate portion of which is parallel with and beneath the axial line of the foot plate 8 fastened in any suitable manner to said frame, so that in use the wheels 2 and 4 are offset, being parallel, the former being journaled on the inner side of the ball of the foot and the latter being journaled on the outer side of the heel, said wheels being arranged on opposite sides of the plate and having parallel axes. It is found by test that this arrangement results in supporting the foot at right angles to the leg, that is in its normal relative position when the body is in a normal healthful standing position. However, the construction thus far described is old, it being described thus fully simply to make clear that in this type of skate the foot from start to completion of the stroke is always kept at 70 the same angle with relation to the leg, the shove being with the heel and laterally instead of with the toe, as in the four wheel, or alined wheel, type, and that thus in this type the natural movement of the foot and 75 leg in skating would at no point result in altering the angle between the foot and leg, so could not result in the unintentional application of the brake.

An ankle brace 18 is pivotally mounted in 80 the frame 6 in a bearing 16 for rocking movement longitudinally of the skate and is of such length as to reach just immediately above the angle of the wearer and is secured to this portion of the wearer's leg by 85 a band 20 to which it is pivotally connected at 21, as shown in Fig. 1. The lower end of the brace carries an arm 24 substantially at right angles to said brace 18 and this arm is provided with a lateral extension substantially at right angles thereto and extending laterally beyond the center of the tread of the tire 4^a mounted on the wheel 4, and a brake shoe 26, shown in the form of a roller by way of illustration only, is mount- 90 95 100 105 110

ed on the above extension and engages the tread of the tire 4^a of said wheel 4 on the brace 18 being rocked toward the rear of the skate to a sufficient degree, the arm 24 5 being shorter than the radius of the wheel 4 and the bearing 16 being located under the plane passing through the axes of the wheels 2 and 4 and in advance of the axis of the rear wheel 4.

10 Thus it follows that a pointing of the toe of the wearer, involving an increase of the degree of angle between the foot and leg of the wearer will result in rocking the brace 18 rearward with relation to the frame 6 15 and therefore in moving the brake shoe 26 into contact with the tire. It follows also that in case the brake be applied in this manner too abruptly the momentum of the wearer's body will carry it forward with relation to the skate until the foot approaches more nearly, or assumes, a position at right angles to the leg, thus relieving the brake as the normal position is approached until the brake is entirely released, thus, with the 20 momentum of the wearer's body, effecting an automatic regulation of the braking operation and saving the wearer from a painful fall in the circumstances above indicated.

25 The plate 8 above referred to is provided with toe clips 10 and 12 and a heel strap 14 for holding the skate securely on the foot of the wearer.

30 The reason for having a short brace 18 extending just above the ankle is to allow 35 for greater rocking movement of the foot on the ankle, which movement becomes more limited in proportion to the height of the point of attachment of the brace 18 to the leg above the ankle.

40 A pneumatic tire 4^a, above referred to, is mounted on the rear wheel 4 and is absolutely essential, as hereinafter explained, in the absence of some other and positive steering means. Also, I prefer to mount a similar pneumatic tire 5 on the front wheel 2, 45 though this is not essential to the steering operation and could well be replaced with a solid cushion or other tire.

45 The pneumatic tire 4^a on the rear wheel 4 has a very intimate association with the other elements of the skate to permit abrupt turns and to facilitate traveling in a straight line at high speed or climbing a hill or traveling against a heavy wind where a 55 strong push with the feet is necessary.

50 It is inherent in this type of skates that so long as they are in a horizontal position they will travel in a straight line corresponding to the axial line of the particular 55 skate. When, however, they are tilted to either side a change in the points of contact of the wheels with the ground is effected, but their axes are still parallel, so that the 60 skate will still travel in a straight line, but 65 at an angle to the axial line of the skate,

and always in the same lateral direction corresponding to the side of the skate on which the rear wheel is mounted.

In traveling at high speed or when skating against a heavy wind or in climbing a 70 hill a strong shove with the heel is necessary and results in tilting the skate, depressing the heel and raising the toe, so that the 75 skate has its course changed at an angle to run laterally outward from under the wearer.

Also, this tilting is essential in quick turning, but without some special provision the 80 skate will travel in a straight line, instead of in a curve.

To meet such circumstances as above mentioned, allowing long powerful strokes for 85 high speed and in hill climbing or skating against the wind and to provide the maximum of control allowing abrupt turns to 90 avoid accidents I have found it absolutely essential to provide the rear wheel with a pneumatic tread which may be deformed by lateral and downward pressure. Under 95 such pressure the tire 4^a is deformed or 100 rolled over between the point of contact with the ground and the rim of the wheel. In deforming this portion of the tire as above, the wheel and rest of the tire is of course forced laterally and as the rest of 105 the tire first engages the ground it is slightly farther outward than the portion immediately before in contact with the ground, thus pulling the rear wheel laterally and so 110 changing the direction of the axial line of the 115 skate. As this pulling action is continuous of course the shifting of the direction of the axial line of the skate is continuous, so that the line of travel may be thus changed from a straight line to a very 120 abrupt arc, as well as all intermediate 125 curves, thus providing very responsive means for correcting the tendency to roll laterally in a straight line from under the 130 wearer on giving a strong shove in any of the situations above mentioned as well as means for making an abrupt turn to avoid accidents.

Having thus described my invention, what I claim as new and desire to secure by Letters Patent is:

1. A skate comprising a pair of offset 135 wheels, the rear wheel being on the outside and the front wheel being on the inside of the skate, and a pneumatic tire mounted on 140 the rear wheel and adapted to give laterally to pressure to pull the rear wheel laterally of the skate to shift the direction of the 145 axial line of the skate.

2. A skate having a frame, offset wheels 150 and a brace, the front wheel being on the inside and the rear wheel on the outside in order to keep the wearer's foot normally at 155 right angles to his leg in the various movements of his foot and leg in skating, in com-

bination with means for retarding the rotation of the rear wheel, said brace being connected to said frame for rocking movement and provided with means for actuating said 5 retarding means as the brace rocks toward the rear of the skate and for releasing said retarding mechanism as the brace rocks to-

ward the front of the skate in case the wearer applies the retarding means too suddenly and is thrown forward by the momentum of his speed. 10

In testimony whereof I affix my signature.

CHARLES HASKELL CLARK.
